UNITED STATES PATENT OFFICE.

FRANK BECKER, OF MCKEESPORT, PENNSYLVANIA.

CUE AND BALL RACK AND TIP-FASTENER.

SPECIFICATION forming part of Letters Patent No. 391,677, dated October 23, 1888.

Application filed February 21, 1888. Serial No. 264,850. (No model.)

To all whom it may concern:

Be it known that I, FRANK BECKER, a citizen of the United States, residing at McKeesport, in the county of Allegheny and State of Pennsylvania, have invented certain new and useful Improvements in Cue and Ball Racks and Tip-Fasteners; and I do hereby declare the following to be a full, clear, and exact description of the invention, such as will enable others skilled in the art to which it pertains to make and use the same, reference being had to the accompanying drawings, which form a part of this specification.

My invention relates to a combined cue and ball rack and tip-fastener; and it consists in a cue-rack of ordinary construction provided at the rear with a rack for storing cues and a number of vertically-moving weights for attaching the tips to the ends of cues, and of pool-ball racks below and drawers for storing the billiard-balls when the same are not in use, together with certain other details of construction and combination of parts, as will be fully set forth hereinafter.

In the accompanying drawings, Figure 1 is a front elevation of my improved rack constructed in accordance with my invention. Fig. 2 is a side sectional elevation of the same. Fig. 3 is a sectional plan view of the rack, taken on the line *xx*.

To construct a combined cue and ball rack in accordance with my invention, I form from suitable timber a double cue-rack, the one *b* at the rear of the other, *a*, and separated the one from the other by the doors *c*, hinged to open outward. These racks *a b* each consists of a base-board, *d*, having small pockets or depressions formed therein, in which the butt of the cues *e* rests, and at the top a perforated or open slotted board, *g*, in which the top por-

tion of the cues *e* is confined. At the top of the rear rack, *b*, and directly above each cue *e* therein, is arranged a weight, *h*, capable of moving vertically over suitable guides, *l*, by means of a cord, *i*, secured thereto, and small bearing-pulley *k*. This weight *h* may be retained at the top of the rack *b* by attaching the cord *i* to a hook, *w*, driven into the rear wall of the rack *b*. Beneath these two racks *a b*, I construct two sets of pool-ball racks, *n*, having an intervening space, *o*, between the two, in which a small basket and brush may be placed. Beneath each of these ball-racks *n* is a drawer, *m*, used for storing the balls used on billiard-tables.

When replacing leathers or tips on the ends of cues, it is necessary that a constant pressure be kept against the same for several hours in order to give the glue or cement an opportunity to become thoroughly set. By placing such cues *e* in the rear rack, *b*, and allowing the weight *h* to rest thereon the tips are firmly attached.

Having thus described my invention, what I claim, and desire to secure by Letters Patent, is—

A combined cue and ball rack consisting of the two racks *a b*, separated the one from the other by the hinged doors *c*, the vertically-moving weight *h* and a means for operating the same, the ball-racks *n*, and drawers *m*, and an intervening space, *o*, substantially as and for the purpose set forth.

In testimony that I claim the foregoing I hereunto affix my signature this 23d day of December, A. D. 1887.

FRANK BECKER. [L. S.]

In presence of—

C. C. LEE,
M. E. HARRISON.
